C. A. STURTEVANT.
PNEUMATIC PAD FOR PRINTING PRESSES.
APPLICATION FILED JUNE 13, 1913.

1,145,276.

Patented July 6, 1915.

UNITED STATES PATENT OFFICE.

CHARLES A. STURTEVANT, OF PLAINFIELD, NEW JERSEY.

PNEUMATIC PAD FOR PRINTING-PRESSES.

1,145,276.

Specification of Letters Patent.

Patented July 6, 1915.

Application filed June 13, 1913. Serial No. 773,417.

To all whom it may concern:

Be it known that I, CHARLES A. STURTEVANT, a citizen of the United States, and a resident of Plainfield, in the county of Union and State of New Jersey, have invented certain new and useful Improvements in Pneumatic Pads for Printing-Presses, of which the following is a specification taken in connection with the accompanying drawing, which forms a part of the same.

My invention relates to pneumatic pads for printing presses.

It relates more particularly to pneumatic pads to be used with the wiping or polishing mechanism of printing presses and to insure the wiping or polishing material, as for example fabric, being pressed at all points with equal pressure against the plate or roll to insure the polishing or wiping material thoroughly and evenly wiping or polishing the plate, roll or other member which is to be wiped or polished.

In the accompanying drawing showing illustrative embodiments of my invention and in which the same reference numerals refer to similar parts in the several figures, Figure 1 is a longitudinal vertical section through one form of my improved pneumatic pad; Fig. 2 is a detail fragmentary vertical section on an enlarged scale; Fig. 3 is a detail vertical section on an enlarged scale and substantially the same view as that shown in Fig. 2, with the exception that the pad is deflated; Fig. 4 is a longitudinal vertical section through a modified form of pad substantially on the line 4-4 of Fig. 6 looking in the direction of the arrows; Fig. 5 is a transverse vertical section substantially on the line 5-5 of Fig. 4 looking in the direction of the arrows and showing in addition one form of platen upon which the pad is usually mounted and also a wiping or polishing fabric; Fig. 6 is a horizontal section substantially on the line 6-6 of Fig. 5 looking in the direction of the arrows; Fig. 7 is a transverse vertical section of a modified form; and Fig. 8 is a sectional view, on a reduced scale, of another form of my pneumatic pad.

In the illustrative embodiments of my invention shown in the drawings, 1 is a pneumatic pad preferably formed dish shaped having an operating face 2 formed of a front member 3, a back member 4, with an

interposed closed air tight chamber 5. I also preferably provide my pneumatic pad with upturned flanges 6, 6. These flanges 6, 6 with the upper surface of the back member 4 form an open receptacle or dish within 60 which fits a platen such as 8 of the printing machine, Fig. 5. The pad is secured directly to the platen by any suitable means such as by the screws 9 passing through the flanges 6, 6, the clamping plates 10, 10 being 65 also preferably used.

I preferably form my pneumatic pad of rubber and reinforcing material, ordinarily some suitable form of fabric, though, of course, my invention is not to be limited to 70 fabric, for any suitable form of reinforcing material comes under the terms of my invention. For purposes of illustration I have shown the back portion 4 formed of a strip 11 of rubber with a reinforcing strip 75 12 of fabric or suitable material, which reinforcing strip extends completely over the rubber strip 11 and preferably up the sides of the upturned flanges 6, 6.

The lower or face member 3 is preferably 80 formed of a thicker strip of rubber 13 which for nearly its entire surface is reinforced by any suitable reinforcing material as fabric 14; this fabric 14 extends nearly to the side 15, 15 but stops substantially at the point 85 16, 16 so as to leave a strip 17 of unreinforced rubber.

The closed air chamber 5 is provided with any suitable valve 18, Fig. 2, to coöperate with a pneumatic pump or any suitable 90 source of fluid supply to inflate the pad 1. In its non-inflated condition the pad is substantially as shown in Fig. 3. When inflated, however, through the valve 18, air or other fluid is forced into the chamber 5 95 which will cause the front member 3 to be forced away from the back member 4. To prevent bellying or unequal expansion of portions of the front face 3, I provide that face with the reinforcing strip 14 which is 100 stopped short of the sides 15, 15. By this construction the member 3 will expand when inflated substantially parallel to the back 4, the entire face member 3 remaining substantially flat for the yielding of the 105 member 3 will be confined to the un-reinforced ends 17, 17, the rubber at that point yielding or stretching as shown in Fig. 2. This will insure whatever material may be 110 beneath the surface 3 being presented against

the plate to be operated on with substantially equal pressure throughout its entire surface. If used with a polishing or wiping mechanism, my pad will insure that all portions of the wiping or polishing material, such as for example the fabric 23, Fig. 5, being pressed with equal pressure against the plate to be wiped or polished, for the front member 3 will not bulge or bow under the pressure of the inflating air, but on the contrary will expand evenly and in its expanded position will be substantially parallel to the back member 4 and the platen 8 to which it is usually connected. In some cases I may further insure the surface 3 being always parallel to the surface 4 by using tying members between the two members 3 and 4, extending through the pneumatic chamber 5. Various forms of such tying or reinforcing members may be used. In Figs. 4, 5 and 6 I have shown longitudinally extending ribs 19, 19 which are preferably of rubber and formed integral with the pad and connect the members 3 and 4 of the operating face. These tying or strengthening ribs 19, 19 do not extend to the ends of the pneumatic pad so that they do not divide the chamber 5 into a plurality of chambers, this chamber 5 in all forms of my invention being simply a single chamber which can be inflated through one valve. Nor do they interfere with the give or elasticity of the un-reinforced rubber portions 17, 17.

Instead of using ribs I may in some cases use one or more connecting teats 20, 20, Fig. 7, connecting the members 3 and 4 together. In all of these cases whether the reinforcing ribs or teats 19 and 20, respectively, are used or not, the expansion or yielding of the pad will take place at the weakened or non-reinforcing portions 17, 17. The ribs 19, and teats 20, when used, simply further insure that the yielding will be confined to these weakened or non-reinforcing portions 17 of the pad, and in all cases a substantially flat operating face 3, and one which is substantially parallel to the member 4 will be presented to the part or member with which the pad is to coöperate in a printing machine.

My invention is equally adapted to be used with rotary printing presses.

I have shown on a small scale in Fig. 8 my pad 25 formed with a concave surface 26 to coöperate with the surface of the roll 27 illustrated diagrammatically in dotted lines. Between my pneumatic pad and the surface of the roller 27 a polishing or wiping material 23 is preferably used. This type of pad is the same as the others except that it is so shaped as to coöperate with a roll instead of a plate. It is preferably formed of rubber having a reinforcing strip of fabric 28 extending up the flanges 29, 29 and is also provided with a reinforcing strip 30 similar

to the strip 14 in the other forms and with weakened unreinforced portions 31, 31, the front and back portions of the pad being connected by members 32, 32 to insure that the pad will expand evenly as in the other forms.

Having thus described this invention in connection with the illustrative embodiments thereof to the details of which I do not desire to be limited, what is claimed as new 75 and what it is desired to secure by Letters Patent is set forth in the appended claims.

1. A pneumatic pad for printing presses comprising a closed pneumatic chamber provided with an upper surface of rubber reinforced throughout its length, a lower surface of rubber reinforced except substantially at the meeting edges of the sides and front face, and unreinforced rubber on the sides of the pneumatic chamber. 80

2. A pneumatic pad for printing presses comprising a closed pneumatic chamber formed of yielding and non-yielding material, the two materials extending entirely around the pneumatic chamber except at the ends where the unyielding material is omitted. 90

3. A pneumatic pad for printing presses comprising a closed pneumatic chamber formed of yielding and non-yielding material, the two materials extending entirely around the pneumatic chamber except at the ends where the unyielding material is omitted, and connecting means extending through the pneumatic chamber and securing the front and back of the pad together. 100

4. A pneumatic pad for printing presses comprising a closed pneumatic chamber formed of yielding and non-yielding material, the two materials extending entirely around the pneumatic chamber except at the ends where the unyielding material is omitted, and integral connecting or reinforcing members extending through the pneumatic chamber and securing the front 110 and back of the pad together.

5. A pneumatic pad for printing presses comprising a dish shaped member having integral upturned flanges to be directly secured to a platen or similar member and provided with a hollow operating face formed of front and back members with an interposed air tight chamber between them, and means upon the inflation of the pad to insure that the front face member will expand substantially parallel to the back member of the operating face. 115

6. A pneumatic pad for printing presses comprising a dish shaped member having integral upturned flanges to be directly secured to a platen or similar member and provided with a hollow operating face formed of front and back members with an interposed air tight chamber between them and connecting members between the front 125 and back members. 130

and back face members to insure the front face member expanding substantially parallel to the back member.

7. A pneumatic pad for printing presses formed of rubber and reinforcing fabric including an operating face formed of side and separated reinforced front and back portions, together forming a closed pneumatic chamber, the reinforcement in the back member extending throughout that member, the reinforcement in the front member extending throughout that member except substantially at its meeting edges with the side members at which points the rubber is not reinforced.

8. A pneumatic pad for printing presses formed of rubber and reinforcing fabric including an operating face formed of side and separated reinforced front and back portions, together forming a closed pneumatic chamber, the reinforcement in the back member extending throughout that member, the reinforcement in the front member extending throughout that member except substantially at its meeting edges with the side members at which points the rubber is not reinforced, and connecting members between the front and back portions extending through the pneumatic chamber.

9. A pneumatic pad for printing presses formed of rubber and reinforcing fabric in-

cluding an operating face formed of side and separated reinforced front and back portions, together forming a closed pneumatic chamber, the reinforcement in the back member extending throughout that member, the reinforcement in the front member extending throughout that member except substantially at its meeting edges with the side members at which points the rubber is not reinforced, and integral upturned flanges to secure the pneumatic pad to a platen or similar surface.

10. A pneumatic pad for printing presses formed of rubber and reinforcing fabric including an operating face formed of side and separated reinforced front and back portions, together forming a closed pneumatic chamber, the reinforcement in the back member extending throughout that member, the reinforcement in the front member extending throughout that member except substantially at its meeting edges with the side members at which points the rubber is not reinforced, and connecting members between the front and back portions extending through the pneumatic chamber.
